CONTAINER FOR A SET OF SOCKET WRENCHES

David D. Kane, Chicago, Ill.

Application August 5, 1946, Serial No. 688,507

6 Claims. (Cl. 206—46)

1

This invention relates to an improved container for a set of right-angled hexagonal socket wrenches, known in the trade as an Allen wrench set.

It is the object of the present invention to provide a tool box for a set of graduated hexagonal socket wrenches which is rugged and economical in construction and which is adapted to accommodate a plurality of hexagonal wrenches in a compact nested relationship so that the individual wrenches are securely held in place and wherefrom they are adapted to be conveniently selected for use in order to facilitate their handling and to prevent their misplacement and possible loss.

It is a further object of the present invention to provide an improved package of a set of hexagonal wrenches of graduated size encompassed in a minimum amount of space while affording maximum protection against displacement and loss. The package is of small size and may be conveniently carried in the pocket of a coat or overalls.

The invention contemplates the nesting of a set of Allen wrenches in a container formed of a bottom and a lid hinged thereto, the former being provided with a shelf for supporting the wrenches of graduated sizes, with spacers for maintaining the wrenches in aligned and nested position, while keeping them separated, with parts of the wrenches protruding from the box to a slight extent in order to facilitate their removal therefrom as well as permitting a clear view of the wrenches from outside of the receptacle. The hinged lid is provided with means cooperating with the wrench set to maintain the complete set of wrenches securely in place on the shelf within the body of the receptacle without any undue rattling.

Other objects and purposes will appear from the detailed description of the invention following hereinafter, taken in conjunction with the accompanying drawing, wherein

Fig. 1 is a plan view of the improved container for the set of right-angled hexagonal wrenches in accordance with the present invention;

Fig. 2 is a front elevation of Fig. 1;

Fig. 3 is a perspective view of the container in open position with some of the wrenches within the container; and

Fig. 4 is a transverse sectional view along line 4—4 of Fig. 1.

In the drawings, the improved container for a set of Allen wrenches A is formed of a box-like receptacle 1 with a lid or cover 2 therefor, hinged along one edge thereof. The box is preferably formed of sheet metal consisting of a base 10 with ends 11 and 12, and edges 13 and 14 pressed up therefrom. The lid 2 is hinged to the top of edge 14 and the opposite edge 13 is formed of a main portion and an auxiliary portion 20 extending angularly thereto and converging towards the edge 14 so that the end 12 is shorter than the end 11. The edges and ends, as well as the in-

2

clined face 20, are bent at right angles from the plane of the sheet 10 and it is only necessary that the meeting edges of these surfaces be in contiguous relationship.

The lid 2 has likewise pressed from the face thereof the ends 21 and 22 and the front edge formed of main portion 25 and the auxiliary angular portion 23 to overlie respectively the ends 11 and 12 and edge portions 13 and 20 of the receptacle 1. The hinged edge of the lid opposite the edge portions 23 and 25 is turned inwardly at the mid-portion thereof, as shown at 35, to form a cylindrical opening for a pintle 26 cooperating with the portions 24 and 26 which are turned outwardly from the opposite ends of the top of the edge 14 of the receptacle 1. This arrangement is clearly shown in Figs. 1, 3 and 4, providing an economical construction for pivotally mounting the lid 2 upon one edge of the receptacle 1.

A shelf 15 is fitted in the receptacle 1 to provide an inclined support for the set of socket wrenches therein, each having a short and a long arm. This shelf is pressed into the base receptacle and securely held therein by the series of vertical walls or flanges extending therefrom.

The flange 16 adjacent the edge 14 extends upwardly from the shelf, while the flange 17 adjacent the edge 13 extends downwardly therefrom (Fig. 4). Furthermore, the vertical flanges 18 and 19 adjacent the end walls 11 and 12 extend upwardly from the face of the shelf 15, as shown in Figs. 2 to 4, and serve to retain the shelf in the receptacle without any auxiliary retaining means. As shown in the drawings, it is not necessary that the flanges extend completely across the respective walls, and the fitting thereof into the body of the receptacle is facilitated by the provision of the cut-out portions 40 at the rectangular corners thereof.

The shelf 15 is provided with three sets of spacers 36, 37 and 38, to maintain the individual wrenches in aligned and nested relationship. The set of spacers 36 and 37 extend in parallel to the long arms of the right-angled wrenches, while the spacers 38 extend in parallel to the short arms of the wrenches. While a set of ten wrenches is shown in the drawings, more or less than this number may be included in the set. The set shown in the drawings includes the following sizes: $\frac{3}{8}''$, $\frac{5}{16}''$, $\frac{1}{4}''$, $\frac{7}{32}''$, $\frac{9}{32}''$, $\frac{5}{32}''$, $\frac{1}{8}''$, $\frac{3}{32}''$, $\frac{5}{64}''$ and $\frac{1}{16}''$.

The inclination of the shelf 15 is such as to accommodate the largest wrench along the edge of the box adjacent the hinge 26 and end 12, and the smallest wrench at the side most distant therefrom. The top edge 41 of the face 20 is inclined corresponding to the inclination of the shelf 15 as shown in Fig. 2. Likewise the bottom edge 42 of the face 23 of the lid is inclined in the opposite direction to confine between the edges 41 and 42 the graduated set of wrenches, the short arms of which protrude to a slight extent from the container. As shown in Fig. 2, the inclination of the edge 42 is lesser than that of the edge 41.

In order to retain the wrenches in place and to prevent their rattling when the container is closed, depressions 30 and 31 of tear-drop configuration are pressed in the top of the lid which present depressions at the inner face thereof at approximately the line of spacers 36 and 37, to confine the wrenches in place. By virtue of the tear-drop configuration of the depressions, these are of greater depth at the side of the box remote from the hinge, corresponding in effectiveness to the inclination of the edge 42 of the face 23 in the cover.

The projection of a small part of the short arms of the right-angled wrenches beyond the inclined edge of the box permits a convenient removal therefrom by a tilting or lifting movement, and in addition provides a convenient check on the completeness of the set even when the container is in closed condition as is obvious from a glance at the front of the box shown in Fig. 2. While the edges and ends pressed from the plane of lid 2 are shown in separated condition in order to overlap the corresponding edges and ends of the base receptacle, they may be continuous if so desired. The same is true of the upstanding edges and ends of the base.

The spacers 36, 37 and 38 may be applied individually to the upper plane of the shelf, may be cut or stamped therefrom, or each set may be applied as a unit to the upper or lower surface of the shelf 15.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A container for a set of hexagonal socket wrenches of graduated sizes comprising a receptacle and a lid hinged thereto along one edge thereof between two ends of said receptacle, said receptacle having the edge opposite said first-mentioned edge formed of two portions, one main portion extending in parallel to said first-mentioned edge and an auxiliary portion disposed angularly with respect thereto and converging towards said first-mentioned edge to form the end adjacent thereto shorter than the opposite edge, said receptacle having an inclined plane shelf therein overlying the base of said receptacle and extending upwardly from said first-mentioned edge towards the top of said receptacle at the opposite edge, and said lid overlying said receptacle to close the same around the complete perimeter thereof with the exception of said auxiliary portion, wherefrom are adapted to protrude the arms of said set of socket wrenches.

2. A container for a set of right-angled hexagonal socket wrenches of graduated sizes each having a long and short arm, comprising a receptacle and a lid hinged thereto along one edge thereof between two ends of said receptacle, said receptacle having the edge opposite said first-mentioned edge formed of two portions, one main portion extending in parallel to said first-mentioned edge and an auxiliary portion disposed angularly with respect thereto and converging towards said first-mentioned edge to form the end adjacent thereto shorter than the opposite end, said receptacle having an inclined plane shelf therein overlying the base of said receptacle and extending upwardly from said first-mentioned

edge towards the top of said receptacle at the opposite edge, and spacers on said shelf for spacing and accommodating the socket wrenches on said shelf starting with the largest adjacent to said first-mentioned edge and shorter end, to the smallest adjacent to the opposite edge, said lid overlying said receptacle to close the same around the complete perimeter thereof with the exception of said auxiliary portion, wherefrom are adapted to protrude the short arms of said set of socket wrenches.

3. A container as set forth in claim 2, wherein the upstanding wall of said receptacle as well as the down-turned wall of said lid at said auxiliary portion are tapered to form an opening of decreasing width from the end to accommodate the graduated sizes of the short arms of the socket wrenches protruding therefrom.

4. A container as set forth in claim 2 wherein are provided two sets of spacers parallel to said first-mentioned edge at two displaced points therealong and a single set of spacers parallel and in proximity to the short end of the receptacle.

5. A container as set forth in claim 2, wherein are provided two sets of spacers parallel to said first-mentioned edge at two displaced points therealong and a single set of spacers parallel and in proximity to the short end of the receptacle, and said lid is provided with a pair of depressions of varying depth on its outer face to form corresponding protuberances on its inner face and overlying said two sets of spacers to press the set of wrenches against said shelf to prevent rattling thereof.

6. A wrench set comprising a plurality of socket wrenches of graduated sizes, each composed of a long arm and a short arm extending at right angles thereto, and a container therefor, said container comprising a receptacle and a lid hinged thereto along one edge thereof between two ends of said receptacle, said receptacle having the edge opposite said first-mentioned edge formed of two portions, one main portion extending in parallel to said first-mentioned edge and an auxiliary portion disposed angularly with respect thereto and converging towards said first-mentioned edge to form the end adjacent thereto shorter than the opposite end, said receptacle having an inclined shelf therein extending upwardly from the base of said receptacle at said first-mentioned edge towards the top of said receptacle at the opposite edge, and spacers on said shelf for spacing and accommodating the socket wrenches on said shelf starting with the largest adjacent to said first-mentioned edge and shorter end, to the smallest adjacent to the opposite edge, said lid overlying said receptacle to close the same around the complete perimeter thereof with the exception of said auxiliary portion, wherefrom are adapted to protrude the short arms of said set of socket wrenches.
